Be it known that I, HIRAM HOWARD, a citizen of the United States, residing at Providence, county of Providence, State of Rhode Island, have invented and produced a new and original Design for Badges, of which the following is a specification, reference being had to the accompanying drawing, forming part thereof.

10 The drawing shows my newly designed badge.

15 The leading feature of my design consists in a four-leaf clover, the surface of each leaf forming a space upon which suitable figures may be formed or mounted.

15 The four-leaf clover will be inclosed in a band or scroll completely surrounding the same, presenting a flat surface between two

In testimony whereof I have signed my name 30 to this specification in the presence of two subscribing witnesses.
